UNITED STATES PATENT OFFICE

2,689,373

APPARATUS FOR FORMING MINERAL WOOL

Charles D. Richardson, Anna, Ill., assignor to
Charles Richardson Corporation, Muncie, Ind.

Application June 25, 1952, Serial No. 295,528

1 Claim. (Cl. 18—2.5)

1

This invention relates to the manufacture of mineral wool and particularly to an improved machine for converting molten slag into fibrous materials.

In forming mineral wool, the modern practice has been to melt the slag or other inorganic material and then subject the molten material to a fluid blast. The material is cooled below its melting point and attenuated into relatively long, soft fibers. The apparatus of the present invention is related to and generally represents an improvement over my earlier and co-pending applications, Serial Nos. 215,463, 278,679 and 237,508, all relating to method and apparatus for forming mineral wool.

It is an object of this invention to provide apparatus for simply and economically forming mineral wool of low density and with a minimum of shot.

A further object of the invention is to provide apparatus for forming mineral wool which will give a greater volume of fiber for the quantity of slag used than any previously known method and apparatus and which will produce fiber of maximum resiliency.

Still another object of the invention is the provision of a spinning head and shaft for such apparatus wherein a cooling fluid is continuously supplied, and wherein such fluid supply is so arranged as to give maximum cooling to the head and shaft without excessively cooling the slag, and wherein the viscosity of the slag may be controlled within given limits.

A further object of the invention is to provide an apparatus having a simplified but improved spinning head.

Another object of the invention is to provide an apparatus wherein the spinning head and its associated nozzle may be set at any desired angle for maximum efficiency.

Still another object of the invention is to provide an improved spinning head and associated blast nozzle wherein the device may be constructed from standard materials cut to size without the need for expensive, special casting.

With the above and other objects in view, as will be presently apparent, the invention consists in general of certain novel details of construction and combinations of parts hereinafter fully described, illustrated in the accompanying drawings and particularly claimed.

In the accompanying drawings like characters of reference indicate like parts in the several views, and:

Fig. 1 is a side elevational view of the appara-

2

tus used in carrying out the method and showing the spinning apparatus in relative position to the well known melting cupola and collection chamber.

Fig. 2 is an enlarged, front elevational view of the improved spinning head and its associated blast nozzle.

Fig. 3 is a cross-sectional view, partly broken away, taken on the line 3—3 of Fig. 2, disclosing important details of the improved spinning head and associated blast nozzle and indicating the travel path of the melt.

Fig. 4 is a cross-sectional view of a modified form of spinning head and which may be substituted, if desired, for the disc form shown in Fig. 3.

In the drawings, the reference numeral 10 indicates the standard cupola in which the slag or other inorganic material is raised to the desired temperature and forms the melt which is fed to the spinner head. The cupola 10 is provided with a spout 11 and the melt travels in a thin stream to the slag through 12 which may be adjustably positioned to direct the stream of slag to the proper spot on the spinning head.

When the fibers are formed by a fluid blast, as will be later described, the blast directs the fibers into the standard settling chamber 13 which is provided with a conveyor belt 14 to carry away the massed fibers for packaging or further processing.

To carry the improved spinning head of the present invention there is provided a table frame 15. The table frame 15 is provided with a top 16 which is pivotally connected to the frame by the hinges 17. To the underside of the table top 16 there is attached a depending frame structure 18 of any desired detail upon which is mounted the motor 19.

The purpose of the hinged top 16 is to permit the spinning head hereinafter described to be set at any desired angle to the horizontal. The mounting of the motor 19 on the structure depending from the table top causes the motor shaft to remain at all times parallel to the shaft of the spinning head.

In order to hold the table top 16 in any selected position the top has pivotally attached thereto a slotted arm 20. Secured to the table is a threaded bolt 21. A thumb screw 22 may be turned down against the slotted arm 20 to lock the arm and the table in fixed position.

Mounted on the table top 16 and secured thereto by the bolts 23 are the journal boxes 24 which house any desired standard type of bearings.

Journalled in the bearings for rotation about its longitudinal axis is the pipe shaft 25 and to the outer end of said shaft is fixedly attached the pulley 26. This pulley is driven by the belt 27 which is driven by the pulley 28 mounted on the shaft of the motor 19.

Concentrically positioned within the pipe shaft 25 is a smaller siphon pipe 29, the inner end of which extends just slightly beyond the inner end of the pipe shaft 25, as is shown in Fig. 3.

At the outer end of the pipe shaft 25 is located a fixed pipe T 30. For joining the fixed T 30 and the rotatable pipe shaft 25 there is provided a high speed, flexible coupling of the siphon type known as the "Barco" joint. A hose or other conduit 32 supplies cooling fluid to the pipe T 30 and a valve 33 controls the movement of such fluid. A hose or the like 34 conducts fluid from the siphon pipe 29.

At the inner end of the pipe shaft 25 is positioned the improved spinning head and its associated annular blast nozzle.

The spinning head includes the cylindrical wall 35 and the end wall 36. The ends of the pipe shaft 25 and siphon pipe 29 project through the end wall 36 into the chamber. A threaded nut 37 is secured by welding or otherwise to the end wall 36 and by means of this nut 37 the spinner head may be threadedly engaged with the inner end of the pipe shaft. To lock the high speed head on the shaft there are provided the lock nut 38 and washer 39.

The cylindrical wall 35 of the spinning head is provided with an outwardly turned annular flange 40. Removably secured to the head by the bolts 42 is the spinning disc 41. This disc 41 may be provided with a slightly cupped surface 43 as shown in Fig. 3, or as extensive experiments have indicated, it may be left flat with fully satisfactory results.

Surrounding the spinner head, as shown in Figs. 2 and 3, is a fiberizing blast nozzle generally designated by the reference numeral 44.

The nozzle is formed of an annular, hollow ring 45 which is substantially square in cross-section. This ring has frame members 46 and 47 attached thereto, as by welding, and bolts 48 securely fasten the cap 44 to the table tap 16.

In the front wall of the ring 45 is formed the substantially continuous slot 49, preferably about .030 in. in width, and through this slot passes the fluid blast, steam or air, which intercepts the fine streams of slag from the spinning disc 41. However, in order to provide a travel path for the stream of molten slag as it spills from the trough 12, approximately two inches of the slot is blocked, preferably by welding, as at 50.

It will be seen that this block purposely breaks the continuity of the annular blast. As the fine streams of slag spin off of the disc 41 in all directions, part of the streams pass at an angle through this break in the curtain of fiberizing fluid. Therefore, to intercept these angularly travelling streams, and at the same time to avoid interference with the main stream which falls vertically onto the disc, there are provided a series of drilled holes 51. These several fluid jets intercept any streams which travel through the break in the curtain at an angle. Since the fine streams will be thrown tangentially from the disc 41 and since the disc is spun in a clockwise direction, as indicated by the arrow of Fig. 2, the streams in the 2" sector will be effectively intercepted by the fluid from the apertures, since these streams must travel transversely of the vertical

line. However, the main supply stream drops vertically and finds its way without interception to the spinner head.

It is necessary that the blast nozzle 44 fit closely around the spinning head or large amounts of shot will be formed. As the steam rushes from the annular slot 49 an area of low pressure is formed in the space between the blast nozzle 44 and spinning head, and cold air in large volume is drawn through the space to form large quantities of shot. To cut off or reduce this air flow to the minimum, the hollow ring 45 is formed with an inwardly directed extension 52. Between this extension and an annular clamping ring 53 is placed an annular sealing gasket or packing 55. The clamping ring 53 is held by machine screws 54. The packing 55 is preferably formed of several layers of wire screen of 16 to 20 mesh but may be of any known material for the purpose not easily broken down by high temperatures.

In order to admit steam or air to the hollow ring 45, there is attached to or formed in the side wall the internally threaded boss 61. This boss is connected by suitable conduits to a source of high fluid pressure, these conduits and connections being designated by the reference numeral 62 and shown fragmentarily in Fig. 1.

The distance between the annular slot 49 and the edge of the spinning disc 41 has been found to be critical, and extensive experiments have shown that this distance must not be over two inches, a distance of one and one-eighth inches being the most effective.

An alternate form of spinning head 56 is shown in Fig. 4. This head includes an end wall 57 which is apertured and threaded as at 58 to receive the pipe shaft 25, a cylindrical side wall 59, and an inset cup 60. This form of spinning head provides increased area for the cooling fluid and also provides a greater surface for cooling the slag as it is carried around the cup and spun off in a plurality of fine streams.

The operation of the device is as follows. The pipe shaft and table top 16 is first adjusted to the desired angle. The apparatus will operate acceptably in a substantially horizontal position as shown in Fig. 1. The centrifugal action of the disc 41 and the aspirator effect of the fluid blast through the annular slot 49 causes a lowered pressure at the center of the disc. The stream of slag drops through the break in the fluid curtain formed by the block 50 and is sucked on to the center of the disc by the lowered pressure. In practice the preferred angle for the shaft and head has been found to be about 45°. The motor 19 is then started and the speed adjusted to the viscosity of the melt. The valve 33 is then opened and cooling fluid is circulated inwardly through the pipe shaft 25 and outwardly through the siphon pipe 29. Steam or high pressure air is then turned into the blast nozzle 44 setting up the blast curtain as shown in Fig. 1. Slag is then directed from the trough 11 in a fine stream on to the spinning disc 41 just slightly above the axial center. A fine spray of slag is then thrown off tangentially from the disc 41 at all points, whereupon it is intercepted by the fluid blast and cooled and attenuated into fibers which are collected in the settling chamber.

It may be emphasized that an important feature of the invention is the fact that the cooling fluid is supplied through the pipe shaft 25 and is discharged through the siphon tube 29. The main problem of an apparatus of this sort is to cool the spinning head and bearings without ex-

cessive cooling of the slag which will cause it to chill and adhere to the spinning head. Usually, the fluid in the return pipe is in the form of steam, since the water circulation must be restricted to avoid chill. The supply of cold water to the pipe shaft cools the shaft and bearings first and to the maximum amount. Within certain limits the control of the fluid flow, and especially in the form of head as shown in Fig. 4, may be used to control the viscosity of the melt and thus the diameter of the fibers.

While there is herein shown and described the preferred embodiments of the invention, it is nevertheless to be understood that minor changes may be made therein without departing from the spirit and scope of the invention as claimed.

What is claimed is:

Apparatus for spinning mineral wool fibers including a hollow cylindrical spinning head, means to rotate said head, means for establishing a flow of cooling fluid therethrough, means for directing a stream of molten material to the outer surface of said head, and an annular blast nozzle closely surrounding said head and having apertures

therein directing a blast of fluid transversely of the edge of said head to intercept the fine streams of molten material thrown tangentially from the head, said blast nozzle further having a resilient

5 sealing ring attached thereto and a free annular skirt contacting the surface of said cylindrical

spinning head at the inner end thereof to seal

the annular space between said blast nozzle and

said spinning head against a current of cold

atmospheric air.
